UNITED STATES PATENT OFFICE.

EWALD KOERNER, OF DRESDEN, GERMANY, ASSIGNOR TO UNITED CIGARETTE MACHINE CO. INC., OF LYNCHBURG, VIRGINIA, A CORPORATION OF VIRGINIA.

TOBACCO-CUTTING MACHINE.

Application filed September 30, 1926, Serial No. 138,588, and in Germany December 10, 1925.

The present invention relates to a type of tobacco cutting machines in which the tobacco is fed into the path of a reciprocating knife. The knife is of flat-blade construction and is held in a carrier, the latter being reciprocated in such manner that the knife is given an endwise movement transversely of the path in which the tobacco is fed. The knife is normally adjusted in such manner as to bear against faces disposed at opposite sides of the opening in the device through which the tobacco is fed.

The present invention has for its object means for adjusting the knife, by movement toward said faces, during the operation of the machine and from a point at the side of the tobacco opening, and to provide such a construction as to enable the use of relatively light compact adjusting means which shall not be subjected to such major stresses as to limit their life and throw undue strain upon the joint connections which are employed therein. Other objects of the invention will hereinafter appear.

The invention will be understood by reference to the accompanying drawing in which—

Figure 1 illustrates in side elevation the upper portion of a tobacco cutting machine embodying the invention, and

Figure 2 is a front elevation of the same;

Figure 3 is an enlarged detail view of certain primary members of the adjusting mechanism in the same position as shown in Figure 2, and

Figure 4 is a sectional enlargement of the adjusting screw and helical gears in side elevation.

In machines of the present type the knife is engaged and directly adjusted by movements of pressure levers, and the said levers are connected with means for moving them on their fulcrums to impart more or less pressure to the knife blade at the lower portion thereof. In the art are disclosed tobacco cutting machines in which the adjustment of the knife may be effected during the operation of the machine, this being accomplished through pressure levers operated by an adjustable spindle carried in a stationary bearing and connected to the screw or screws of the pressure levers by means of universal joints. In such devices the universal joints must be of very substantial construction, and the knife holder has

been unnecessarily heavily loaded, further objections being that the adjustment means as a whole were in front of the knife and thus obscuring the cutting action and obstructing access to the cut tobacco. 60

In the present invention the machine comprises a frame 1 of any suitable construction, to which a pair of spaced swinging levers 2 are pivoted. The levers at their front ends are bent upwardly at substantially right angles and support between them the knife carrier 3. In the knife carrier the knife 4 is held in the usual manner.

The knife carrier is reciprocated by means of a crank rod 5 operatively connected to a crank shaft 5^x which is rotated in the usual manner. In view of the fact that the knife carrier is connected to the ends of the swinging levers 2, the carrier follows the arcuate path described by the levers. 75

On the knife carrier 3 are pivoted on a shaft 7 two double-arm pressure levers 6. The lower end of each lever presses the knife against the faces 18^x of the tobacco opening or channel 18, and the upper end of each lever is provided with a threaded aperture to receive the threaded stem of an adjusting screw 8. Each screw passes through a yoke member 1^x forming a part of the upper end of the appropriate swinging lever 2 85 and is held against endwise movement in said yoke through the fact that it is keyed to a helical gear 10, the side faces of which abut the arms of the yoke. Each adjusting screw is provided with a hand wheel 9, so that the screws may be rotated by the hand wheels while the machine is at rest. 90

Helical gear 10 is in mesh with a similar gear 11, the latter being carried by shaft 12 mounted in the bearing extensions 13 of yoke 1^x. Shaft 12 is connected to a second shaft 15 by a universal joint 14. Shaft 15 extends to the right hand frame member 1 and passes through a bearing 16 which is free to rotate. In other words, the bearing 16 has a ball and socket connection with the said frame member 1. At the right hand end of shaft 15 is provided a hand wheel 17 by means of which shafts 15 and 12 may be rotated to actuate the helical gears 10 and 11 and thereby rotate adjusting screw 8, the action of the latter being to swing the appropriate pressure lever in such direction as to clamp or release the knife blade. 105

As the knife carrier is reciprocated by the 110

action of crank rod 5 and controlling swinging levers 2, shaft 12 will be bodily swung and shaft 15 will have a slight endwise movement in rotary bearing 16, as indicated by the dotted lines, Figure 3. It will be noted that the movement of the hand wheel is very slight. Such movement will not be sufficient to prevent the ready rotation of the hand wheel and adjustment of the knife while the latter is in action. It is possible to adjust either one of the pressure levers, or both together, in either direction, while the machine is operating at a high rate of speed.

By means of the present invention it is possible to employ light universal-jointed shafts to transmit the required pressure on the knife, and to greatly reduce the inertia of the parts, which inertia was present owing to the constructions of the prior art devices.

Having described my invention, what I claim and desire to secure by Letters Patent is as follows:—

1. In a device of the character described, a blade, a blade carrier, means for reciprocating the blade carrier, a pressure lever bearing on the blade and means for actuating said pressure lever comprising an adjusting screw thereon, universally jointed spindles extending approximately at right angles to the adjusting screw, a hand wheel carried by one spindle, and gears interposed between and operatively connected to the spindles and the adjusting screw.

2. In a device of the character described, a blade, a blade carrier, means for reciprocating the carrier, a pressure lever bearing on the blade, and means for adjusting said pressure lever comprising a member carried by the lever and so mounted as when rotated to rock the lever, a spindle extending substantially at right angles to said adjusting member, gear connections intermediate said adjusting member and the spindle, a hand wheel carried by the spindle, and supporting means for the spindle permitting both lateral and endwise movement thereof.

3. In a device of the character described, a blade, a blade carrier, and means for reciprocating the carrier, spaced pressure levers pivotally mounted on the carrier, a yoke member supported by the carrier for each pressure lever, a gear mounted intermediate the arms of the yoke, an adjusting shaft passing through the yoke and keyed to the gear, the shaft being threaded in an aperture formed in the appropriate pressure lever, a second gear supported by the yoke, and spindle and universal joint connections intermediate said second gear and a hand wheel, said connections being disposed substantially at right angles to the adjusting screw, and the hand wheel being disposed at one side of the knife.

In testimony whereof, I have signed my name to this specification.

EWALD KOERNER.
